UNITED STATES PATENT OFFICE.

FRANK J. TISDELL, OF LYNN, MASSACHUSETTS, ASSIGNOR OF ONE-FOURTH TO CHARLES B. DAVIS, OF LYNN, MASSACHUSETTS, AND ONE-HALF TO GREGORY & READ CO., OF LYNN, MASSACHUSETTS, A CORPORATION OF MASSACHUSETTS.

TOP-LIFT-BURNISHING MACHINE.

1,349,863.

Specification of Letters Patent. Patented Aug. 17, 1920.

Application filed May 31, 1919. Serial No. 301,075.

To all whom it may concern:

Be it known that I, FRANK J. TISDELL, a subject of the King of Great Britain, and a resident of Lynn, county of Essex, State of Massachusetts, have invented an Improvement in Top-Lift-Burnishing Machines, of which the following is a specification.

This invention relates to a machine for ironing, burnishing, or otherwise finishing the edges of the leather top-lifts which are usually attached to wood heels, this operation usually being performed before the heel is attached to the shoe.

Prior to my invention it has been customary to perform this work with a rotary burnishing iron, the heel being held in the hands of the operator and pressed thereagainst.

This method has many well known disadvantages. For example, it requires a considerable degree of skill on the part of the operator. It is slow and severely taxes the strength of the operator after a time.

The object of my invention is to provide a machine for performing this work, which will enable the same to be easily, rapidly and satisfactorily performed by comparatively unskilled labor.

I accomplish this object by the means shown in the accompanying drawing in which:—

Figure 1 is a side elevation of a machine, embodying my invention.

Figs. 2 to 4 are detail views of the heel base engaging clamp member, which I employ.

Figs. 5 to 7 are sectional views taken at line *a*, *a* of Fig. 1, showing the parts in different positions.

Fig. 8 is a plan view of the work supporting means when turned to a horizontal position.

In the drawings, a preferred embodiment of my invention is shown, which comprises a base 1, having vertically adjustable bearings 2 mounted therein, in which a horizontal shaft 3 is journaled, said shaft having tight and loose pulleys 4 and 5 thereon. A rotary burnishing iron or tool 6 is mounted on one end of said shaft, said tool being of a form commonly employed for this purpose, having an oblique edge-burnishing face 6^a, and a tread-face-engaging flange 6^b.

According to my invention, I provide on

the base 1 a pair of vertically disposed guideways, 7 and 8, (see Figs. 1 and 8) in which a yoke, or U-shaped frame 9 is mounted to slide, and means are provided for lifting said yoke, comprising a vertically disposed rod 10, to which a foot treadle 11 is attached, said rod passing directly through the base of the machine.

A U-shaped clamp frame 12, having arm portions 12^a and 12^b, is mounted between the arms of said yoke 9 to swing about an axis parallel to, and in the same vertical plane as, the axis of the shaft 3, by means of a stud 13 which projects from the arm 12^a into arm 9^a, and a rod 14, which passes through the arms 9^b and 12^b and is slidable therein, said stud and rod being arranged in axial alinement. A U-shaped arm 16 is formed integrally with clamp frame 12 and extends from arm 12^b, in opposite relation thereto, longitudinally of rod 14 and then transversely, so that its end portion extends into the axial line of said rod, said frame 12 and arm 16 forming, in effect, a double crank.

A coiled spring 18 is arranged on the stud 13, between said frame arms, said stud being slidable in the arm 9^a, and said spring being normally adapted to hold the clamp frame approximately in the position shown in Fig. 1.

A coiled spring 20 is provided on the rod 14 between the arm 9^b and a collar 21, and normally acts to push said rod to the right. A clamping screw 22 is threaded in the end portion of the arm 16 and is arranged in axial alinement with the rod 14, and in position to engage the end thereof to force the same to the left, against the action of spring 20.

A heel base clamp member is provided, which consists of a plate 24, having a convex face adapted to fit in the concaved face in the base of an ordinary wood heel, said plate preferably having brads 25 in its face, to assist in holding the heel in position and a notch 24^a in its lower end, to receive the adjacent portion of the clamp frame 12, and hold the same in upright position. Connections are provided between the rod 14 and said plate 24 permitting the latter to be held at any required angle, according to the pitch of the heel, the particular means shown comprising a round bar 26, which is supported

by a central bolt 27, said bolt passing transversely therethrough and being supported in a socket, formed therefor in the adjacent end of rod 14, said bar 26 being held in a 5 horizontal position against the rear side of the plate 24 by two pairs of projecting pins 28 mounted in the plate, as shown in Figs. 1 to 4.

A pull spring 30 is connected to the rear 10 side of plate 24 and to the frame arm 12^a and acts to draw the plate against an adjustable stop, such as the screw 31, on the frame, when the clamp is opened to release a heel.

A short projection 32, having a vertically 15 disposed flat face at its end, is formed on the inner side of the clamp arm 12^a, said face and the work-engaging side of the tool-flange 6^b being normally held in the same vertical plane, and said face being arranged 20 to form the top-lift engaging member of the clamp.

The manner in which the device is operated may be described as follows:—

A wood heel *x*, with the leather top-lift *y* 25 attached, is placed in the clamp with the top-lift against the projection 32, and the hand screw 22 is turned so as to force the rod 14 inward, to press the plate 24 against the heel base, so that the heel will be 30 clamped securely in the position shown in Fig. 1.

The tool 6 is constantly rotated at a high rate of speed, its position with relation to the heel clamp being adjusted in the direction 35 of its axis, if necessary, by changing the position of the pulleys 4, 5 on the shaft 3.

The clamp frame 12 and arm 16 at, or near the points indicated by the characters H and H', respectively, are adapted to provide 40 hand holds, and, in practice, the operator grasps the hand-hold H with his left hand, and the hand-hold H' with his right, and, at the same time, depresses the treadle 11 with his foot, lifting the yoke 9, and with 45 it the clamp 12, holding the heel, so that the edge of the top lift is engaged with the face 6^a of the tool, and, at the same time, the clamp is moved axially, so that the flange 6^a of the tool bears against the treadle-face of the lift, as indicated in the dotted line position of Fig. 1.

The clamp is then manually moved rotatably about its axis, the clamp frame 12 and arm 16 acting as cranks, so as to cause 55 the iron to operate on the lift edge throughout its entire length, except the breast edge, as indicated in Figs. 5 to 7. As the edge of the lift is not concentric with the axis of the clamp, the latter is raised and lowered as it 60 is rotated by varying the pressure on the treadle, the force with which the lift is held against the tool being entirely controlled thereby.

In moving the lift into engagement with 65 the iron, the clamp is not only moved

axially, so that the flange 6^a of the iron will bear against the lift face, but, as this face is likely to be more or less out of true, *i. e.*, not exactly flat, more or less axial motion of the clamp is usually necessary, while it 70 is being rotated. Also, to form a sharp, and well finished edge on the top lift, the lift must be pressed with some force against the flange 6^b, while pressed against the surface 6^a.

In practice, therefore, the heel is moved in three different ways at the same time, said movements being vertical, horizontal and rotational.

When the operation is finished, the frame 80 9 is permitted to rest on the base, and, to unclamp the heel, the screw 22 is turned back, permitting the spring 20 to move the rod 14 in the same direction, and the spring 30 to draw back the plate 24, with the rod 85 14, until the bottom portion engages the stop screw 31. When the plate is in this position, another heel may be readily placed in position.

The operation is thus rapidly performed. 90 I claim:—

1. A machine for finishing the edge of a top-lift of a heel comprising a rotary tool having an edge-finishing portion and a tread face engaging flange, a yoke having 95 manually controlled means to move it transversely of the axis of the tool, a heel-clamp frame, having heel-clamping members, said frame being pivotally mounted at its ends in the arms of said yoke and arranged to be 100 manually moved about an axis parallel to the axis of the tool, and longitudinally thereof, to permit the thread face of the top-lift to be held against said flange while its edge is engaged with the edge-finishing portion of the tool, as the heel is moved rotatably and transverse axially.

2. A machine for operating on the edges of the top lifts of heels comprising a tool mounted to rotate about a horizontal axis, a vertically movable yoke, a heel-clamp frame having relatively movable heel clamping members and having pivots at its ends arranged to support it in the arms of said yoke in position to permit it to be manually 110 swung about an axis parallel to the axis of said tool and to be slid longitudinally of said axis, and manually controlled means for raising and lowering said yoke to hold the top-lift against the tool while the frame is 115 manually moved on its pivots.

3. In combination with a tool mounted to rotate about a horizontal axis, a vertically movable frame disposed beneath said tool, a U-shaped heel-clamp mounted in said frame 125 and freely movable about an axis parallel to the axis of said tool, said clamp having a heel-top-engaging face fixed on the inner side of one of its arms and a heel base engaging plate between its arms, said face and 130

plate being arranged to hold a heel adjacent the axis of said clamp, means movable in line with said axis to adjust said plate toward and from said face, and means under 5 direct control of the operator for yieldingly sustaining said frame to hold a heel supported by said clamp in position to be operated on by said tool.

4. In combination with a tool mounted to 10 rotate about a horizontal axis, a vertically movable frame disposed beneath said tool, a heel clamp comprising two arms and a rigid intermediate connection, one of said arms being pivotally engaged with said frame at 15 its outer side, and having a heel-top engaging face at its inner side, and the opposite arm having a longitudinally adjustable rod passing therethrough in axial alinement with said pivot, and providing a pivotal 20 support for said clamp, a heel-base engaging plate disposed between said arms and arranged to be forced by said rod toward said 25 face, means for forcing said rod longitudinally to clamp the heel, and means for yieldingly supporting said frame in position to hold a heel carried by said clamp in position to be operated on by said tool.

5. In combination with a tool mounted to 30 rotate about a horizontal axis, a vertically movable frame disposed beneath said tool, a heel holder comprising a pair of double crank arms pivotally mounted in said frame to swing about an axis parallel to the axis 35 of said tool and oppositely arranged with relation to the axis about which they swing to provide oppositely disposed hand holds 40 for controlling the rotative movements of said holder, heel clamping members mounted between one pair of arms, one of said 45 members being stationarily disposed at the inner side of one of said arms and the other of said members having adjusting means comprising a rod adjustable in line with the axis of said rod and a screw threaded in the 50 end arm of the other pair of arms to force said rod toward the stationary clamp member, and manually controlled means for holding said frame in position to engage a heel carried by said clamp with said tool.

55 6. In combination with a tool mounted to rotate about a horizontal axis, a frame guided to move vertically beneath said tool, a U-shaped heel-clamp having a stud at one end and a clamp member adjusting rod at the opposite end, said rod and stud being 60 arranged in axial alinement and supported in said frame providing a pivotal support

for said clamp, an arm rigid with said clamp and having means arranged to engage said rod to hold the same in adjusted position 65 and means for sustaining said frame in position to hold a heel carried by said clamp in position to be operated on by said tool.

7. In combination with a tool mounted to rotate about a horizontal axis, a frame 70 guided to move vertically beneath said tool, a U-shaped heel-clamp pivotally mounted in said frame and manually movable axially and rotatably therein and manually controlled means for raising said frame to support a heel carried by said clamp in position to be operated on by said tool in the different positions of axial and rotary adjustment thereof.

8. In combination with a tool mounted to 75 rotate about a horizontal axis, a yoke mounted to move vertically beneath said tool, a U-shaped frame mounted between the arms of said yoke to rotate about an axis parallel to the axis of said tool and having a fixed 80 and an adjustable heel-clamping member respectively carried by the opposite arms of said frame, a U-shaped arm rigidly connected to, and extending from said frame, and having means at its extreme end for controlling the position of said adjustable member, said U-shaped arm and frame providing hand holds for the manual control thereof, and manually controlled means for sustaining said yoke in operative relation 85 with said tool.

9. In combination with a tool mounted to 90 rotate about a horizontal axis, a yoke mounted to move vertically beneath said tool, a U-shaped frame disposed between 95 the arms of said yoke, a pivot stud extending between two of the adjacent arms of said yoke and frame and a rod extending through and longitudinally movable in the other two arms thereof, in axial alinement with said 100 pivot stud and providing therewith means for supporting said frame in said yoke in position to be moved rotatably about an axis parallel to the axis of the tool, a heel-clamping plate arranged between said arms 105 in position to be engaged by the adjacent end of said rod, and an arm rigid with said frame and having means to engage the opposite end of said rod to force the same axially to clamp a heel between said plate and the arm of said frame opposite thereto.

In testimony whereof I have signed my name to this specification.

FRANK J. TISDELL.
